UNITED STATES PATENT OFFICE

92,151

DESIGN FOR A PNEUMATIC DISPATCH TUBE CARRIER OR SIMILAR ARTICLE

John T. Needham, North Plainfield, N. J.

Application January 23, 1934, Serial No. 50,491

Term of patent 14 years

To all whom it may concern:

Be it known that I, JOHN T. NEEDHAM, a subject of the King of Great Britain and a citizen of Canada, residing in North Plainfield, in the county of Somerset and State of New Jersey, have invented a new, original, and ornamental Design for a Pneumatic Dispatch Tube Carrier or Similar Article, of which the following is a specification, reference being had to the accompanying drawing, forming a part thereof.

Fig. 1 is a front view of a carrier showing my new design; and

Fig. 2 is a side view thereof.

I claim:

The ornamental design for a pneumatic dispatch tube carrier or similar article substantially as shown.

Signed by me at New York city, in the county of New York and State of New York, this 18th day of January, 1934.

JOHN T. NEEDHAM.
